UNITED STATES PATENT OFFICE

2,428,153

MANUFACTURE OF WELT SHOES

Henry Gottlieb, Montreal, Quebec, Canada

Application April 21, 1944, Serial No. 532,037
In Canada December 31, 1943

1. Claim. (Cl. 12—142)

1

This invention relates to the manufacture of shoes and the object is to provide an improved process for the manufacture of welt shoes of the box-toe type.

According to this invention the shoe upper is formed in the usual manner and the toe portion is then subjected to a pressure molding operation to form a substantially rigid box-toe. A sock lining and a welt are then stitched to the toe and shank portions of the upper and the resulting assembly is then fitted on a last so that the sock lining covers the bottom or sole portion of the last. A filler sole and an outsole are then initially secured in place by gluing the forepart and shank of the filler sole to the sock lining and then gluing the forepart and shank of the outsole to the corresponding portions of the filler sole and to the welt, the heel portions of the filler sole and outsole being tacked or otherwise secured to the heel portion of the upper, following which a heel is then nailed to the heel portion of the outsole in the usual manner. The partially finished shoe is then removed from the last and subjected to the usual finishing operations in the course of which the outsole is sewed to the welt.

The moulding of the toe part of the upper, followed by the sewing of the sock lining and the welt to the forepart and shank portion of the upper, constitute the essential novel steps of the process described herein. These preliminary operations enable the cushion sole and the outsole to be lasted to the forepart of the upper without the use of tacks and also ensures the formation of a box-toe having perfectly smooth inner and outer surfaces which do not wrinkle in service.

In the preferred practice of this invention a toe stiffener, consisting of a piece of fabric impregnated with asphalt or other suitable adhesive stiffening substance, is inserted between the toe portion of the upper and the toe lining prior to the aforesaid toe molding operation. In this case the toe portion of the upper is heated and softened by a steaming or other heating operation before being subjected to pressure between the toe shaping molds by means of which the stiffened toe portion of the upper is molded to provide a substantially rigid box-toe. During the molding operation the softened asphalt in the toe stiffener serves to adhesively unite the upper, the toe stiffener and the toe lining in such manner as to ensure the provision of a toe cap having perfectly smooth molded inner and outer surfaces which will not wrinkle in service.

Proceeding now to a more detailed description

2

of this invention reference will be had to the accompanying drawings, wherein—

Fig. 1 is a side view of an upper equipped with toe and counter stiffeners secured in place between the upper and the upper lining.

Fig. 2 is a longitudinal sectional view of the upper assembly shown in Fig. 1.

Fig. 3 is a view showing the manner in which the stiffened toe portion of the upper is molded 10 between male and female mold members to provide a substantially rigid box-toe in which the upper and the toe lining are fused to the toe stiffener.

Fig. 4 is a view showing the stiffened toe portion 15 of the upper after it has been transformed into the substantially rigid box-toe by the molding operation illustrated in Fig. 3.

Fig. 5 is a perspective view showing the manner 20 in which the sock lining and the welt are secured to the upper following the molding operation.

Fig. 6 is a view similar to Fig. 5 showing the upper after it has been fitted on a last following the attachment of the sock lining and welt.

Fig. 7 is a view showing the filler sole after it 25 has been lasted in place.

Fig. 8 is a view showing the outer sole lasted in place and the heel applied.

Fig. 9 is a perspective view of the finished shoe showing the outsole sewed to the welt.

Fig. 10 is a sectional view taken substantially 30 along the line 10—10 of Fig. 5.

Fig. 11 is a transverse sectional view taken substantially along the line 11—11 of Fig. 6.

Fig. 12 is a transverse sectional view taken substantially 35 along the line 12—12 of Fig. 7.

Referring to Figs. 1 and 2, 5 designates a shoe upper which is formed in the conventional manner. A toe stiffener 6 is secured in place between the toe portion of the upper and the forepart lining 7. A counter stiffener 8 is also secured 40 in place between the heel portion of the upper and the lining 9.

The toe stiffener 6 is preferably composed of a piece of fabric impregnated with asphalt or with 45 some other suitable adhesive stiffening compound.

According to my invention the upper assembly 50 shown in Figs. 1 and 2 is first placed in a steam box (not shown) or is otherwise heated and softened to prepare it for the toe molding operation. The toe portion of the upper is then subjected to shaping pressure between the upper and lower toe shaping mold members 11 and 12 shown in Fig. 3, the upper female mold member 11 being 55 stationary and the lower mold member 12 being

raised and lowered by mechanism including an operating handle 13.

The toe molding operation transforms the relatively limp toe portion of the upper into a substantially rigid box-toe of substantially the shape shown in Fig. 4. During the molding operation the toe portion of the upper and the opposing portion of the toe lining are pressed smoothly against the toe stiffener 6 and fused thereto by the adhesive action of the softened asphalt with which the toe stiffener is impregnated. Following the molding operation a sock lining 14 and a welt 15 are then stitched to the toe and shank portions of the upper as shown in Figs. 5 and 10 so that the welt lies substantially parallel with the outer surface of the upper. In order to prevent cracking of the upper during the subsequent lasting operations, it is desired that the upper be again heated and softened by steaming or otherwise before being fitted on the last. The resulting assembly is then placed on a last 16 as shown in Fig. 6. The sewn edges of the upper, sock lining and welt are then worked inwardly over the bottom of the last in the usual manner (Figs. 6 and 11) to thereby dispose the welt 15 in a position extending outwardly from the upper substantially at right angles thereto, the welt being retained in the latter position by reason of its inherent stiffness and shape. A filler sole 17 is then glued to the sock lining as shown in Figs. 7 and 12, the heel portion of the upper being lasted over the heel portion of said filler sole and tacked thereto. An outsole 18 is then secured in place as shown in Fig. 8, the forepart of the outsole being glued to the forepart of the filler sole and to the welt, the heel portion of said outsole and a heel 19 being tacked in place in the usual manner. The partially completed shoe is then removed from the last and subjected to the usual finishing operation to produce the finished shoe (Fig. 9) in which the outsole 18 is sewn to the welt as indicated at 20.

In making certain types of shoes the toe stiffener 6 may be dispensed with. In this case the toe portion of the upper will be softened by moistening same prior to the toe molding operation illustrated in Fig. 3, as in the case when a toe stiffener is used.

Having thus described what I now conceive to be the preferred embodiment of this invention it will be understood that various modifications may be resorted to within the scope and spirit of the invention as defined by the appended claim.

I claim:

The method of making box-toe welt shoes which comprises forming an upper, inserting a toe stiffener at the front thereof, subjecting the toe part of the upper to a molding pressure in a toe-shaping mold to form a substantially rigid box-toe, without flanging the lower edge of the upper, removing the upper from the mold and attaching a sock lining and a welt to the upper by a single sewing operation in which the toe and shank portions of the sock lining are edge-sewn to the inner side of the corresponding portions of the upper while the welt is edge-sewn to the outer side of the upper so that it lies parallel therewith, fitting the resulting assembly on a last so that the sock lining covers the bottom or sole portion of the last, turning the sewn edges of the upper, sock lining and welt inwardly over the last to dispose the welt in a position projecting laterally from the upper substantially at right angles thereto, gluing the fore part and shank of a filler sole to the sock lining, tacking the heel portion of the upper in place over the heel portion of the filler sole, gluing the fore part of an outsole to the forepart of the filler sole and to said welt, then tacking in place the heel portion of the outsole and a suitable heel and then removing the partially completed shoe from the last and sewing the outsole to the welt.

HENRY GOTTLIEB.
